United States Patent Office

Des. 186,242
Patented Sept. 29, 1959

186,242

DOORKNOB

Leo J. Maffei, New Britain, Conn., assignor to The American Hardware Corporation, New Britain, Conn., a corporation of Connecticut

Application October 17, 1956, Serial No. 43,394

Term of patent 14 years

(Cl. D50—3)

FIG. 1.

FIG. 2.

FIG. 3.

FIG. 4.

FIG. 5.

Fig. 1 is a plan view of a doorknob embodying my new design.

Fig. 2 is a side elevational view thereof.

Fig. 3 is a front end view of said doorknob.

Fig. 4 is an elevational view of said knob, partially in central vertical section, illustrating the contour of the outer end thereof.

Fig. 5 is a plan view of the doorknob, partially in central horizontal section, further illustrating the contour of the outer end of the doorknob.

I claim:

The ornamental design for a doorknob, substantially as shown.
